UNITED STATES PATENT OFFICE.

MATTHIAS P. ZINDORF, OF SEATTLE, WASHINGTON.

ROAD-GRADING DEVICE.

1,282,162.

Specification of Letters Patent. Patented Oct. 22, 1918.

Application filed December 21, 1914, Serial No. 878,218. Renewed May 6, 1918. Serial No. 232,936.

To all whom it may concern:

Be it known that I, MATTHIAS P. ZINDORF, a citizen of the United States, and a resident of Seattle, in the county of King and State of Washington, have invented certain new and useful Improvements in Road-Grading Devices, of which the following is a full, true, and exact specification.

My invention relates to road grading machines and has for its principal objects; to provide improved means to keep the machine in its forward course in a predetermined direction; to provide adjustable draft means to limit the depth of the digging element; to provide adjustable means to limit the depth of the digging element beneath the surface of the ground and to relieve the subsequent strain upon the machine; to provide an improved arrangement which assures the travel of the wheels on a prepared level surface; to provide novel means for the control of a guide tractor wheel; to provide novel means for relieving the strain on the mold board and generally assisting in controlling the machine; to generally improve the details of construction of a machine of the above general character. A further object is to provide a digging element having a vertical adjustment. Other objects will appear as my invention is more fully described in the following specification, illustrated in the accompanying drawings and pointed out in the appended claim.

In the drawings, Figure 1 is a plan view of my machine with parts broken away. Fig. 2 is a side elevation of Fig. 1 with certain parts removed. Fig. 3 is an enlarged cross section on line $x-x$ of Fig. 1. Fig. 4 is an enlarged inside elevation on line $y-y$ of Fig. 1. Fig. 5 is an enlarged view of a mold board on line $z-z$ of Fig. 1. Fig. 6 is a detail of a tractor wheel.

Referring now more particularly to the drawing, numeral 1 designates a land side having stiffening members 2 and 2^a which secure said land side to a body 3 which is of general V shaped contour, as shown in Fig. 1, having an outstanding leg 3^a . A shoe 4 is removably secured to the outer face of body 3 and may project slightly below the lower edge of said body. The said shoe has slotted holes 4^a which allow a vertical movement of the rear part of the shoe, thereby depressing the forward or digging point 5 which projects below the rest of the shoe.

The leg 3^a of body 3 has a longitudinally curved outer face which corresponds to a similarly curved mold board 6 which is hinged to leg 3^a at 7. The body 3 has a curved sharp cutting member 8 attached thereto. The mold board 6 is disposed at an acute angle relative to land side 1 and adjustably braced therefrom by a brace 9 which is hinged to the mold board 6 at 9^a , 65 the other end of brace 9 is hinged to a bracket 10 which supports a toothed tractor wheel 11 and is secured to brace members 2 and 2^a which are offset at 2^b and 2^c respectively. The teeth of tractor wheel 11 project somewhat below the bottom of brace member 2^a and are adapted to dig into the ground and assist in holding land side 1 in a true course and prevents skidding sideways under the unbalanced resistance of the 75 earth against the mold board. That portion of the land side and the stiffening member 2^a which is below line A, in Fig. 3, also projects into the earth and assists in holding the machine in proper alignment. 80 A toothed wheel 12 having a concaved face is located near the rear end of land side 1 and serves a similar purpose to that of wheel 1. A pilot wheel 13 has bearing in a fork 13^a which has vertical adjusting means 85 relatively to a supporting yoke 14 which extends forwardly from body 3 and is in line with land side 1. The wheel 13 runs upon the ground ahead of the digging point 5 and thereby limits the depth of the said digging point below the surface of the ground. 90 As the earth is loosened by the digging member 5 it is forced in a lateral direction by mold board 6, which may be adjusted to suit the conditions of operation as previously mentioned, by brace 9. A cutting edge 6^a on the mold board also loosens up additional earth in the path of the said mold board, which forces the earth laterally. 95 The depth of cut to be taken by the mold board 6 is regulated by an adjustable elevating wheel 15 which is mounted in a laterally swinging fork 16. The fork 16 may be elevated or depressed by means of a lever 17 which is pivoted at 18 to mold board 6. 100 Link 19, and hand lever 20, which is pivoted to mold board 6 at 20^a , operate lever 17. Hand lever 20 has the usual quadrant 21 and latch 22. If the wheel 15 is depressed thereby raising the rear of mold board 6, 105 the cut of said mold board is lightened and vice versa. An adjustable rod 23 is fastened

to one end of mold board 6 and the other end to a draft rig yoke 24. Yoke 24 is secured to an extension bar 25 which is loosely bolted to body 3 at 26. Other corresponding holes 27 are provided in body 3 and bar 25 which allows the attaching bolt 26 to be moved to other holes, thereby changing the point of attachment of the draft rig in such a manner as to cause the digging point 5 to either dig deeper or shallower as desired. Yoke 24 is provided with holes 28 and 29 to which a tongue 30 is bolted by bolts 28^a and 29^a respectively. It will be understood that the tongue 30 may be bolted to any pair of holes 28 and 29 and thus may stand in line with or at an angle with land side 1 as desired. By changing the location of the tongue the point of pull is varied, thereby partly compensating for the unbalanced force caused by the earth pressing against the mold board which force tends to make the rear end of the machine skid toward the land side. When it is desired to travel with the machine, the wheel 15 is thrown down to its lowest position thereby raising the rear of mold board 6 clear of the ground and the trailer wheel 31, which is mounted in a yoke 32 and which in turn is pivotally mounted in a socket lever 33, is lowered by said lever 33 and connecting hand lever 34. Lever 33 is fulcrumed at 35 and is held in guides 36 which prevent lateral motion of said lever. A wedge shaped block 37 which is thinner at one side than the other serves to hold yoke 32 in a fore and aft position, as shown in Fig. 1, when in the raised position, and to the right said yoke into this position as the wheel is raised by means of the said yoke striking against the sloping face of block 37 and thereby being straightened up as shown. Block 37 is secured to land side 1. Hand lever 34 is pivoted at 38 to a support 39 from land side 1 and is provided with a latch 40, and quadrant 41 similar to hand lever 20. Traction wheel 31 may also be used to assist in limiting or regulating the depth of cut to be made by the plow by being lowered until it rolls along, on the surface of the finished ground. It will be noted that when the machine is moving earth, the wheels 11, 12, 16 and 31 all travel upon the previously prepared or graded surface of the ground, thereby maintaining

the machine in true plane. It will be understood that by means of the afore mentioned adjustments, the depth of digging of either end of mold board 6 and digging point 5 may be regulated by the operator as the machine is being drawn over the ground by any motive power. Also that earth may be moved from high points and dropped in lower ones by the operation of the mold board with my machine. Any desired crown or slope of road may be formed by varying the depths of the various digging elements of the machine.

While I have shown a particular form of embodiment of my invention, I am aware that many minor changes therein, will readily suggest themselves to others skilled in the art, without departing from the spirit and scope of the invention, and I therefore, desire to avoid being limited to the exact form shown and described, except as defined in the appended claim.

Having described my invention, what I claim as new and desire to protect by Letters Patent, is—

In a grading apparatus, the combination of a V-shaped frame, one member of which extends rearwardly at an acute angle with reference to the companion member, a skeleton frame attached to the latter member, a land side attached to the outside of the skeleton frame, trailer wheels mounted between the skeleton frame and the land side, a point having a series of inclined slots, fastening means passing through the slots to the V-shaped frame, said slots permitting of the tilting of the forward end of the point with reference to the land side, a mold board hinged to the acutely disposed member of the V-shaped frame, an adjustable brace between the mold board and the skeleton frame, a yoke secured to the upper part of the V-shaped frame, a brace extending from the yoke to the rear end of the mold board, a wheel mounted at the rear end of the mold board, and a system of levers on the mold board for raising and lowering the wheel to tilt the forward end of the point.
